UNITED STATES PATENT OFFICE.

GEORGE C. KIDDER, OF SALT LAKE CITY, UTAH.

FURNACE OR STOVE CONSTRUCTION.

1,226,082.

Specification of Letters Patent. Patented May 15, 1917.

Application filed March 27, 1916. Serial No. 86,891.

To all whom it may concern:

Be it known that I, GEORGE C. KIDDER, a citizen of the United States, residing at Salt Lake City, in the county of Salt Lake and State of Utah, have invented certain new and useful Improvements in Furnace or Stove Construction, of which the following is a specification, reference being had therein to the accompanying drawing.

10 The invention relates to improvements in a furnace or stove construction, and more particularly to a furnace of the steam boiler type.

It is the object of the present invention to 15 provide a furnace wherein large quantities of low grade bituminous coal may be introduced into the burning retorts disposed adjacent the combustion chamber, and communicating therewith, whereby the smoke 20 and gases generated from the bituminous coal are consumed in the combustion chamber by commingling with the heated air led thereto. The gases and smoke generated from the burning coal within the retorts pass 25 through somewhat restricted passages on their way to the combustion chamber at which time they are thoroughly mixed with superheated air immediately upon their entrance to the combustion chamber, so that 30 this air is mixed with the smoke and gases before it comes in contact with the boiler flues, and while it is in a very heated condition. This insures positive combustion of these products and greatly increases the efficiency of the furnace.

The preferred embodiment of the invention consists of relatively large coal retorts surrounded by water jackets and disposed on each side of a combustion chamber, in 40 which the large charges of bituminous or other low grade coal are placed, and in order to insure the proper burning of the coal within the retorts a plurality of air drafts are led thereto, which manifestly permits a 45 very hot fire to be had within the retorts, or to cause the retorts to be heated only to the necessary point, depending, of course, upon the steam required to be generated by the boiler. The retorts rest upon a suitable 50 grate and communicate with the combustion chamber at their lower ends by means of restricted passages, so that the smoke and gases generated from the burning coal are led to the lower portion of the combustion 55 chamber. Disposed adjacent the inlets to the

combustion chamber are suitable air inlet pipes through which superheated air is passed to commingle and mix with the smoke and gases issuing from the retort very soon after these products have reached the combustion chamber. The combustion chamber overlies a suitable grate so that a direct air draft through the grate from the ash pit is derived, which assists greatly in the combustion of the smoke and gases within the combustion chamber causing the furnace to have great efficiency.

While my invention is particularly applicable for use in connection with furnaces of the steam boiler type, I wish it to be understood that the same may be used with an ordinary heating stove, at which time the flues would, of course, be eliminated but the gases and smoke issuing from the retort would be consumed in the combustion chamber in a manner as heretofore specified.

In the drawings:

Figure 1 is a vertical sectional view of the preferred embodiment of my invention;

Fig. 2 is a cross section on the line 2—2 of Fig. 1;

Fig. 3 is a side elevation; and,

Fig. 4 is a detail view of one of the air feeding devices.

Referring now more particularly to the drawings, wherein like numerals indicate corresponding parts, the numeral 1 designates a furnace of the steam boiler type having a wall 2 inclosing the boiler tubes 3 within the combustion chamber 4. Disposed on each side of the combustion chamber and communicating therewith through the openings 5 are the retorts 6 and 7, resting upon the grate 17' which extends entirely across the structure and having water legs 8 and water containing top portions 9. While I have shown a furnace having two of these retorts applied thereto, I wish it to be understood that my invention is not limited to the use of two of these retorts as it has been found that good results can be obtained with but the use of a single retort where the heating plant is relatively small and used, for instance in private houses.

As each of the retorts is of the same specific construction, it is thought that a description of one will suffice for both. A description of the retort 7 will, therefore, be given. This retort is water jacketed to prevent the escape of heat therefrom, and is

separated from the boiler tubes on one side by the water leg 10 depending therefrom to a point near the bottom of the retort, and there resting upon the air conveying pipe 12, 5 to be later described.

At the lower end of the retort is a curved plate 13 having spaced apertures in its lower end and suitably supported on lugs 14 disposed inwardly from the walls of the 10 retort, to support the bituminous coal within the retort in such a manner that air is permitted to enter thereto through the pipe 15 to assist in the combustion of the coal. A 15 cleaning door 20 is arranged adjacent the plate 13, and as the plate 13 prevents coal from falling therebeneath it is obvious that it also permits the insertion and removal of the cleaning instruments through the door 20. A down draft 21 connected with any 20 suitable source of air supply enters the retort at its upper end, and the air issuing therefrom passes downwardly through the coal within the retort for the purpose of 25 promoting combustion. Manifestly, these air supplying ports may be controlled by suitable dampers so as to regulate the fire within the retort. In the construction illustrated water is introduced into the water leg surrounding the retort by the pipe 22 30 communicating with the water in the boiler, and insuring a continuous flow into the water leg. A suitable steam outlet 24 is disposed at the upper portion of the retort jacket to permit the steam generated to escape. A door 25 for the replenishment of 35 the coal within the retort is provided, this door passing through the jacket of the retort and being disposed near the top thereof. From the foregoing it will be seen that the 40 retort is provided with three sources of air supply, one being the down draft issuing through the port 21, another air supply being led to the retort through the air feeding aperture 15, at its lower end while it is apparent that air also passes through the grate 45 17' and acts on the fuel resting thereon.

When fire is started within the retorts the coal in the lower portion of the retort is the first to be burned, the fire then eating its 50 way upwardly through the coal within the retort, the coal last burned lying against the outer walls of the retort.

The coal within these retorts is what might be termed coked, and the smoke and 55 gases issuing therefrom pass through the restricted openings 5 at the lower portion of the retort and there intermingle with the air following the direction of the arrows passing through the grate 17'. The water 60 legs 10 of the boiler rest at their lower ends upon the air supplying members 12, which directly underlie the lower ends of the water legs and somewhat restrict the passage establishing communication between the combustion chamber 4 and the retort 7. These 65

air conducting members are of the same construction and a description of one will answer for both.

Each air supplying member is substantially rectangular in form and carries on its upper side an upstanding lug 26, spaced a slight distance from the end of its water leg to form a pocket into which infusorial earth or fire clay is placed to render the joint air tight. The inside face 28 of the air conducting member is somewhat heavier than the remaining portions thereof and is traversed by a series of narrow vertically disposed recesses 29, which recesses assist in retaining the coal when the retorts are filled while virtually increasing the depth of the coal from which smoke or gas may freely emerge without increasing the width of the retort. The air supplying members are supported by means of lugs 29' adapted to engage coöperating surfaces to support the members. While the specific supporting means employed is one which is highly successful, it will of course be understood that any convenient or conventional type of support may be utilized.

The air supplying members, there being preferably two shown, on each side of the combustion chamber are all of the same detail construction and a description of one will therefore suffice for all. Each air supplying member is provided with a division wall 30 extending horizontally through the same and also vertically disposed division walls 30' dividing each chamber and extending part way lengthwise through each chamber and with the horizontal division wall and providing chambers 31, 32, 33 and 34, the chamber 32-34 are separated from the chambers 31 and 33, it being understood that the object of dividing each member into independent chambers is to provide a means for directing the heated air into the combustion chamber in different directions and in different quantities from the separate chambers. Air is admitted to the chambers on one side of the retort through the passage 34' communicating with the external atmosphere, while the air is admitted to the chambers on the other side of the retort by the pipes 35' shown as broken away in Fig. 2.

The air so introduced is caused to travel through these chambers their entire length, the ends of the chambers being closed by the wall 40, and after the air has passed the entire distance through the chamber it is then permitted to enter the discharging chambers 31 and 32, but it is apparent that the air when entering these discharging chambers is in a highly heated condition due to its travel through the chambers 33 and 34. The air in this manner takes a circuitous course, and cannot be delivered to the dis- 125 130

charging chambers until it is in a highly heated condition. The discharging chamber 32, being fed with air in the manner above described, is provided in its face with a series of spaced alternately arranged relatively small ducts 41, permitting only a very small supply of air to be released therethrough, which air takes the course indicated by the numeral 43' and completely commingles or mixes with the smoke and gas as the same is passing to the combustion chamber. The out-going jets of air maintain a horizontal direction for a considerable distance from the air supplying member, and being in a highly heated condition completely mix with the gas from the coal, and ordinarily this is all that is essential to complete combustion of the gases. However the upper chamber 31 has disposed therein a series of obliquely disposed slots 41', this chamber being somewhat smaller than the chamber 32, but the air passing therethrough is well heated and the discharges issuing therefrom supply a film of air that mixes along side the gases being consumed and destroys any slight spray of smoke or other gases which may for some unaccountable reason be free within the combustion chamber, and not mixed with the air to such an extent as to cause their complete combustion. The smoke and gases thus entering the combustion chamber, which is common to both of the retorts, is subjected to three different sources of air supply, one being the updraft passing through the grate, while the other air supplies issue in a horizontal direction from the chambers 31 and 32. The air issuing from the chambers is highly heated due to the circuitous course which it is forced to travel prior to its discharge and when the same enters the combustion chamber it is therefore heated to such a degree as to accomplish the result sought. In order that the gases and smoke may be completely consumed before they in any way come in contact with the water tubes of the boiler suitably disposed baffle plates 43 adapted to be placed in a somewhat staggered relation are provided, and the baffle plates are positioned directly under the boiler and supported by lugs 45 or in any other suitable manner. These baffle plates are utilized in view of the fact that it has been found that as soon as the smoke and gases come in contact with the boiler they are so cooled as to render their combustion practically impossible, even if they are mixed with the incoming heated air in suitable quantities.

Directly underlying the grate 17' are the ash pits 46, which pits are preferably separated by the division wall 47, in such a manner that the retorts and the combustion chamber are provided with independent ash pits. In cleaning the furnace it is only nec-

essary to insert a suitable instrument within the door openings 20 in the retorts, which permits the burned coal on the grate to be shaken or forced into the different ash pits if desired.

Having thus described the invention, the operation may be briefly stated as follows: Coal is introduced into the retorts 6 and 7 and a suitable fire is then started. The retorts are preferably water-jacketed for a purpose which will be obvious to those skilled in the art, and leading to the retorts are the air supplying pipes or air drafts 15 and 21, which assist in promoting combustion of the fuel within the retorts, while air is also introduced into the retorts through the openings in the grate. During the burning of the coal the smoke and gases issuing therefrom pass through the restricted openings 5 into the combustion chamber 4, that is common to all the retorts and directly upon their entrance into the combustion chamber the smoke and gases are subjected to the action of the air entering the apertures in the grate, and the highly heated air issuing from the air supplying chambers 31 and 32, whereby the products entering the combustion chamber from the retorts are completely consumed and always ignited, which greatly increases the efficiency of the furnace. Of course, the supply of air to the combustion chamber and the supply of air to the retorts may be regulated at any time to meet with the demand placed upon the furnace.

While I have illustrated the device as used in connection with a steam boiler furnace, the same is applicable to small heating plants of any type without departing from the invention.

Having thus described my invention what I claim is:

1. A furnace of the character described having a combustion chamber, a retort adjacent thereto adapted to receive a relatively large supply of fuel during the burning thereof and having a communication with the combustion chamber for the passage of the gases generated from the fuel in the retort, an air supplying means conveying air to the combustion chamber to mix with the gases led thereto, said air supplying means consisting of a conduit disposed below the inner wall of the retort and having a plurality of independent air chambers therein, each chamber being provided with spaced discharge openings facing the combustion chamber, one air feeding chamber being disposed above the other, for the purpose described.

2. A furnace of the character described comprising a combustion chamber, a retort for burning fuel adjacent thereto and in communication with the combustion chamber an air supplying conduit of substan-

tially rectangular formation directly underlying the inner wall of the retort and having a plurality of division walls therein dividing the chamber into independent air 5 passages, each passage having discharge openings facing the combustion chamber, means for introducing air to each of said passages, substantially as described.

3. A furnace of the character described, 10 comprising a combustion chamber, a retort on each side of said chamber, for burning fuel and having communications with the combustion chamber to permit the gases generated in the retorts to enter the combustion chamber, air supplying conduits disposed beneath the inner walls of each retort having a plurality of division walls therein dividing each conduit into independent air chambers, said chambers having 15 spaced air feeding openings therein facing the combustion chamber for permitting the escape of air to the combustion chamber to mix with the gases led thereto, substantially as described.

25 4. A furnace of the character described comprising a combustion chamber, a retort on each side of said chamber for burning fuel and having communications with the combustion chamber to permit the gases 30 generated in the retorts to enter the combustion chamber, air supplying conduits disposed beneath the inner walls of each retort having a plurality of division walls therein dividing each conduit into independent air 35 chambers, said chambers having spaced air feeding openings therein facing the combustion chamber for permitting the escape of air to the combustion chamber to mix with the gases, the said air chambers being arranged one above another and the discharge 40 openings therein being of different dimensions.

5. A furnace of the character described 45 having a combustion chamber, a retort adjacent thereto adapted to receive a relatively large supply of fuel and communicating with the combustion chamber for the discharge of the gases generated from the fuel in the retort, air supplying means for introducing air to the combustion chamber 50

comprising a member having independent air chambers therein disposed at different heights, each of said chambers being provided with spaced discharge openings of different dimensions for feeding the air to 55 the combustion chamber, for the purpose described.

6. A furnace of the character described having a combustion chamber, a retort adjacent thereto adapted to receive fuel during the burning thereof and having a communication with the combustion chamber, independent air supplying passages for conveying air to the combustion chamber to mix with the gases led thereto, said supplying 60 passages having discharge nozzles of different dimensions facing the combustion chamber and discharging directly into the combustion chamber, and one of the chambers being arranged above the other, for the 65 purpose described.

7. A furnace of the character described comprising a combustion chamber, a retort communicating therewith and adapted to receive a suitable supply of fuel, independent 75 air feeding members each having a series of nozzles therein facing the combustion chamber for discharging air thereto to mix with the gases entering the chamber from the retort, the nozzles of each series being of different dimensions and disposed one above another, for the purpose described.

8. A furnace of the character described having a combustion chamber, a fuel receiving retort adjacent thereto and in communication with the chamber, a water jacket surrounding said retort and having a downwardly extending water leg, an air supply conduit directly underlying the water leg for feeding air to said chamber, 85 said conduit having a plurality of recesses in its inner face for retaining the fuel in the retort, and means for feeding air to said conduit.

In testimony whereof I affix my signature 95 in presence of two witnesses.

GEORGE C. KIDDER.
